DESIGN FOR A VESTEE

Nini Turcotte, New York, N. Y.

Application September 8, 1941, Serial No. 103,200

Term of patent 3½ years

To all whom it may concern:

Be it known that I, Nini Turcotte, a citizen of the Dominion of Canada, residing in the Borough of Manhattan, county of New York, and State of New York, have invented a new, original, and ornamental Design for a Vestee, of which the following is a specification, reference being had to the accompanying drawing, forming part thereof.

Fig. 1 is a front view of a vestee showing my new design.

Fig. 2 is a rear view thereof.

I claim:

The ornamental design for a vestee, substantially as shown.

NINI TURCOTTE.
